UNITED STATES PATENT OFFICE.

EDWARD GERMER, OF ERIE, PENNSYLVANIA.

STOVE.

Application filed March 7, 1925. Serial No. 13,842.

This invention is designed to improve and render more available the full capacity of gas stoves. To this end the stove is provided with a frame with a permanent gas burner and an extension on which there is arranged a removable oven. The removable oven is locked in place on the extension so that the full efficiency from the oven may be had and at the same time it gives to the stove when the oven is in place an appearance of permanence which adds to its attractiveness. Features and details of the invention will appear from the specification and claim.

15 The invention is illustrated in the accompanying drawings as follows:—

Fig. 1 is a perspective view of the stove from the front of the stove.

Fig. 2 an end view of the stove, a part 20 being broken away to better show construction.

Fig. 3 a section of the front edge of the stove on the line 3—3 in Fig. 1.

Fig. 4 a section on the line 4—4 in Fig. 1.

25 Fig. 5 an enlarged view of the locking hook on the oven.

1 marks the stove frame, 2 burner openings in the stove frame, 3 a manifold along the front of the stove, 4 valves controlling 30 the burners under the openings 2, and 5 a shelf above the frame carried by a bracket 6, the stove being provided with the back 6^a. An oven extension 7 is arranged on the frame 1 and this is provided with an oven 35 burner 8 with a burner opening 8^a and this is controlled by a valve 7^a. A removable oven 9 is adapted to be placed on the extension to cover the same and it is provided with an opening 10 adapted to register with the opening 8^a so that the oven may be heated from the burner 8 which burner is also designed to act as a broiler burner along the lines of the invention set forth in my application, Serial Number 7,845, filed Feb.

9th, 1925. The oven is provided with a door 45 11 opening on an invisible hinge 12 toward the front of the oven, the door forming a shelf in front of the oven when open.

A hook 14 is arranged at the rear of the oven and is adapted to hook into a slot 15 50 in the frame of the extension. By tilting the oven to the position shown in Fig. 2 the oven may be removed. When dropped to place the hook tends to lock the oven in place on the stove top, the oven being of a 55 size to completely cover the extension and thus to give the appearance of a permanent part of the stove.

The oven has a lip 18 at its front edge 60 which overlaps the front edge of the extension. When the oven is in its lower position this edge tends to lock the oven in place on the stove and to close the opening between the oven and the top of the stove. The shelf 5 is left without a bracket at the oven 65 end of the shelf and with the oven in place gives the appearance of a permanent structure of stove. The oven has a flange 16 which engages the rear face of the back 6 so as to close the opening between the oven 70 and the back when the oven is in place and at the same time assists in locking the oven in place on the top.

What I claim as new is:—

In a stove, the combination of a frame 75 having an oven opening; a burner under the opening; a removable oven over the opening; and means locking the oven in place on the frame comprising a downwardly extending hook on the oven and an upwardly 80 opening slot on the frame forming a connection at the rear of the oven with the oven in place over the opening and a depending lip on the oven overlapping the front of the frame.

In testimony whereof I have hereunto set my hand.

EDWARD GERMER.
